UNITED STATES PATENT OFFICE

2,259,143

ELECTRIC HEATER

Jacob L. Shroyer, Oak Park, Ill., assignor to Edison General Electric Appliance Company, Chicago, Ill., a corporation of New York

Original application December 21, 1937, Serial No. 181,014. Divided and this application October 28, 1938, Serial No. 237,518

4 Claims. (Cl. 219—37)

This invention relates to electric heaters, more particularly to electric heaters of the "hotplate" type, such as are used for the surface heating elements of electric ranges and the like, and it has for its object the provision of an improved heater of this character.

More specifically, this invention contemplates an improved organization in a heater of the "hot-plate" type involving improved means for supporting the heating element of the heater. It further contemplates the provision of improved heat reflector means, and of means for supporting the reflector means below the heating element. In addition, this invention contemplates an improved terminal structure for the heater.

This application is a division of my copending application, Serial No. 181,014, filed December 21, 1937.

For a more complete understanding of this invention, reference should be had to the accompanying drawings in which Fig. 1 is a perspective view illustrating an electric range provided with electric heaters arranged in accordance with this invention; Fig. 2 is an enlarged plan view of the electric range of Fig. 1 with parts broken away and in section so as to illustrate certain details of construction; Fig. 3 is a vertical sectional view taken through the line 3—3 of Fig. 2 and looking in the direction of the arrows; and Fig. 4 is a view similar to Fig. 3, but taken through the line 4—4 of Fig. 2 and looking in the direction of the arrows.

Referring to the drawings, this invention has been shown in one form as applied to the electric range of the heavy-duty type described and claimed in my above-mentioned copending application. As shown, this range comprises a top plate section 10. This section 10 comprises a compartment defined by a pair of side walls 11, a rear wall 12, a top plate 13 and a front wall 14, that is formed by a series of panels.

The top plate 13 is provided with a relatively large rectangular opening 15 in which the heating or cooking units 16 are received. The cooking units 16 in the form of the invention shown in the drawings comprise two high-temperature, quick-heating elements 17 arranged at the front, two lower-temperature hotplates 18 arranged back of them at the rear, and a relatively large heavy-duty griddle 19 arranged at the right-hand side of the range. All of these cooking units are removable, and it is to be understood that their proportions are such that they may be interchanged. For example, the griddle 19 may be dispensed with and in its place there may be used two high-speed surface units 17, or two hotplates 18, or one of one and one of the other. Moreover, if desired, one each of the units 17 and 18 may be eliminated and a second large griddle 19 may be used instead of them. Prefer-

ably and as shown, the heating units will be formed into rectangular shapes.

Each high-speed, high-temperature heating unit 17 comprises a pair of sheathed heating elements 20 and 21 supported on a grid 22 which in turn is supported by a top plate 23. The top plate 23 is provided with an opening 24 having in general a circular shape and in which the heating elements 20 and 21 are received. A down-turned flange 25 (Figs. 2 and 4) is provided at this opening. This downturned flange is provided with longer depending tabs 26 in which the ends of the grid 22 are received. The plate 23 is square and at the four sides is provided with a down-turned flange 27 which functions to support the top plate and the heating elements that are mounted within it. The down-turned flange 27 rests upon brackets 28 at their front corners; these brackets are rigidly secured to a flange 28a extending downwardly from the top plate 13 around the opening 15. The down-turned flanges 27 at the rear of the heating elements, as well as those at the front, rest upon beams 29 extending crosswise of the range from side to side and spaced at intervals from the front to the rear, as clearly shown in Figs. 2, 3 and 4.

The heating elements 20 and 21 may be of any suitable type, but preferably will be of the sheathed type such as described and claimed in United States patent to Charles C. Abbott No. 1,367,341, dated February 1, 1921. Briefly, these heating elements comprise a resistance conductor (not shown) mounted in a metallic sheath 30 (Figs. 1 and 4), and supported in spaced relation with reference to the sheath by a suitable powdered, heat-conducting, electrically-insulating material, such as magnesium oxide, (also not shown).

Terminal sections 31 of each heater unit 17 are brought out laterally from the heater, as shown in Figs. 2 and 4, and in the ends of these sections suitable terminals 31a are mounted. To these terminals suitable electrical supply leads 32 are connected. In order to protect the terminals 31a and the leads 32 and the electrical connections between these members from the grease, liquids and the like drippage from vessels placed upon the range, the terminal sections 31 are directed upwardly and thence downwardly as clearly shown in Fig. 4. This prevents grease and other liquids from running along the sheathed heater units to their terminals. As a further protection, the sheathed heaters are provided with washers or baffles 33 adjacent their ends to intercept any grease or liquid which might possibly run along the heaters toward their ends.

In addition, each of the heating units 17 is provided with a reflecting pan 34 which houses the heating elements 20 and 21 as well as the grids 22, as clearly shown in Fig. 4. The re-

fecting pan preferably is provided with a circular side wall, as shown in Figs. 2 and 4, and also is provided with a bottom wall 35 in which there is a centrally arranged transverse depressed section 36 (Fig. 2) having its bottom sloping downwardly from the sides to the center where a drain opening 37 is provided. The pan at one edge is provided with a cut-away section 38 (Fig. 2) through which the terminal ends of the heater project laterally from the heating elements. The reflector 34 rests upon the supporting beams 29 which are provided with cut-away sections 39 to receive the reflectors, as clearly shown in Figs. 2 and 4, and is clearly shown in these figures, the reflector is prevented from moving laterally by the cut-away sections. A relatively large spillage pan 39a is provided under the heating elements.

It will be observed in view of the foregoing construction that the heating elements 20 and 21 with their grids 22 and tops 23 may be moved out of the opening in the top of the range, and also that the reflectors 34 may be conveniently removed. This facilitates the cleaning of the heating units and reflector.

The reflectors may be conveniently removed by tilting up the edges of the heating units 17 at their terminal edges on the brackets 28 and then withdrawing the reflectors laterally, the brackets 28 constituting auxiliary supporting means provided for this purpose. The leads 32, as shown, are sufficiently long to permit the heating units 17 to be elevated a sufficient distance from the cooking top to provide room for cleaning them. If desired, the outer flange 27 for each of the heating plates 17 may be provided with spaced downward extensions 27a (Figs. 2 and 4) at the rear of the side walls arranged to closely interfit with the upper edges of the beams 29. This assists in holding the heating units in place.

Each hotplate 18 comprises a rectangular mass 40 formed of any suitable heat-conducting material, such as cast iron. This mass 40 is provided with a ground and polished cooking surface 41. Cast within the body 40 are one or more sheathed heating elements 42 of substantially the same type described in connection with the heating plates 17. The plates 18 also are supported on the brackets 28 at the rear and on the beams 29, as shown in Figs. 2 and 4, and in the same manner that the plates 17 are mounted, except that in this case the brackets 28 are at the rear of the plate. Also, the unit 18 is provided with spaced downward extensions 42b arranged to tightly fit the upper edge of the flange 29, as shown in Fig. 4, to assist in holding the unit 18 in place. Here also, the terminal ends 42a of the heating elements 42 are directed upwardly and then downwardly to protect the terminals 43, and here also, the heaters will be provided with intercepting baffles 44 to further protect these terminals. Leads 44a similar to the leads 32 are connected to the terminals 43.

The griddle 19 is in general of the same construction as the plate 18 having a heating body 45 formed of a suitable heat-conducting material, such as cast iron, and in which the sheathed heating elements 46 are cast. These elements have substantially the same construction as those described in connection with the plates 17 and 18, and they are connected to suitable leads 46a. As shown, the griddle 19 is supported at the rear and front on brackets 28 and likewise is supported intermediate the brackets by means of the spaced

beams 29. The griddle also has spaced depending members 46b closely fitted over one of the beams 29, as shown in Fig. 3, to assist in holding the griddle in place. The griddle 19, however, is provided with a grease trough 47 extending along its sides and front, as shown in Figs. 1 and 3. The grease and liquids draining off the griddle during the cooking operations collect in this trough, and drain through a discharge spout 48. A suitable grease collecting vessel 48a will be placed under the spout.

The beams 29 are supported at their ends by U-shaped brackets 49 which at their upper ends are directed through openings provided for them in elongated brackets 50 secured to the side walls 11 of the top plate section in any suitable manner, as by welding. On the upper ends of the legs of the brackets 49 are nuts 51 (Fig. 2) which are turned in tightly to hold the beams in place.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. A heating plate for an electric range and the like comprising a sheathed heating element having terminals projecting from the ends of the sheath, the end sections of said sheath adjacent said terminals extending outwardly laterally, said laterally extending sections being curved upwardly and thence downwardly so that the terminals project downwardly and outwardly, and washer-like intercepting baffles on said down-turned portions.

2. In an electric range having a cooking top with an opening therein, transverse beams below said opening, a top plate mounted on said beams, a sheathed heat generating element formed into a plurality of turns, means securing said heat generating element to said top plate so that the plate supports said element in said opening, a reflector pan under said heat generating element resting on said beams as a separate unit from said heat generating element and said top plate so that when said top plate and its heat generating element are elevated in said opening said reflector pan can be removed bodily from said beams and upwardly through said opening.

3. In an electric range having a cooking top with an opening therein, a heating element mounted in said opening, transverse beams below said opening, a support for said heating element resting on sections of said beams, a relatively deep pan-like reflector below said opening and said heating element, and said beams having cut-away sections to receive said reflector to support it below said heating element and to prevent lateral movement thereof with reference to said heating element.

4. An electric range comprising a top plate having an opening therein, a heating unit having a heating element and a top plate in which said heating element is mounted, said top plate being provided with a peripheral down-turned flange, supporting beams upon which said flange rests, and certain portions of said flange having down-turned extensions interlocking with one of said beams to stabilize said top plate and the heating element mounted therein on said beams.
